UNITED STATES PATENT OFFICE.

JOHN GEORGE BRENNER, OF HULME, MANCHESTER, ENGLAND.

GARMENT-HANGER.

1,104,099.

Specification of Letters Patent.

Patented July 21, 1914.

Application filed April 25, 1913. Serial No. 763,649.

To all whom it may concern:

Be it known that I, JOHN GEORGE BRENNER, a subject of the King of Great Britain and Ireland, and resident of Hulme, Manchester, England, have invented certain new and useful Improvements in Garment-Hangers, of which the following is a specification.

This invention refers to and consists of 10 a cloth-covered frame-like coat or like hanger the cloth of which incloses the parts and when distended corresponds in contour with that of the shoulders and neck of the coat to be supported, thus preserving the 15 shape of the coat. The improved hanger is or may be adapted to fold when not in use and when folded to remain folded until forcibly opened out.

Upon the accompanying drawing, Figure 20 1 illustrates a side perspective view and Fig. 2 a geometric plan of the improved hanger as it appears when extended and ready for use. Fig. 3 illustrates a side perspective view of the framework of the hanger when 25 opened out, and Fig. 4 illustrates a perspective end view of the same framework when closed up. Fig. 5 illustrates the improved hanger in use. Fig. 6 illustrates a modification of Fig. 3.

According to the invention the improved 30 hanger consists of two half-frame parts each composed of two narrow strips of metal a^1, a^2 bent to the outline of one half of the intended hanger in plan, and each pivotally 35 connected at its ends to the turned down ends of a plate b . The length of this plate is preferably about half the width of the hanger at its broadest part and the strips a^1, a^2 at one end are each bent inward and toward the end of the plate, thereby leaving 40 a gap c at one side of the hanger. Directly above the plate b , but central to the width of the hanger, is a further plate d and by means of further narrow metal strips e^1, e^2 , 45 bent approximately U-shape, the plate d is secured to the strips a^1, a^2 , the connections being of a pivotal character to allow of the framework folding up as hereinafter described.

Inclosing the framework, and secured 50 along its edges to the strips a^1, a^2 , the strips e^1, e^2 and the plate d is a covering of textile material h . This covering is tightly distended on the frame and forms the upper 55 outer face of the hanger, its longitudinal curvature and transverse arching corre-

sponding to the contour of the shoulders and neck of the coat to be suspended. Connected at one end by a hook i to the plate d and at the other end by a hook j to the plate b 60 is a spiral spring k . Under the tension of the spring and owing to their being pivotally connected to the strips e^1, e^2 the strips a^1, a^2 tend to rotate on their pivots and thus hold the cloth taut; see Figs. 1 and 2. In 65 this condition the hanger, with a hook l applied to the plate d , is ready for use.

It should now be seen that the improved hanger affords a support for the coat or other like garment to be suspended which 70 conforms to the shape of the shoulders and fills the garment at such point from back to front as well as from shoulder to shoulder, thereby insuring that the garment shall not 75 lose its proper shape.

To the plate d is applied a hook m from which a trousers hanger n may be suspended, the gap c affording the necessary room for the trousers hanger to hang within the coat. The trousers hanger may be of the spring- 80 tongue type engaging the bottoms of the trousers legs, the trousers being inverted, see Fig. 5. Part of the cloth is omitted on one side the hanger. Of course, the improved hanger may be made without the hook m , 85 in which case the strips a^1, a^2 , may be the same at both ends, see Fig. 6 and the plate b be the full width of the hanger, while the cloth also completely covers both sides. When not required for use the hanger is 90 folded back upon itself, see Fig. 4, the two strips a^1, a^2 and the cloth being turned back on their pivots until they meet above the hook l when, owing to the parts of the strips at such point lying closer together than the 95 pivoted ends of the strips and owing to the pull of the spring k , the hanger remains folded and can thus be stowed away in small compass. While preferring narrow strips of metal for the framework, it will be understood that the framework may be made 100 of other materials.

What I claim is:—

1. A coat or like hanger, comprising two 105 half-frame parts, a plate to which the half-frame parts are pivotally connected, the said half frame parts and plate in plan corresponding to the length and width of the shoulders of a coat, a further and shorter plate directly over the first named plate, 110 means for pivotally connecting the upper plate to the half-frame parts and holding

the upper plate at the required distance from the lower plate, a spring connected at its ends to the two plates respectively and by its tension holding the plates at their shortest distance apart, a covering of cloth for the upper parts of the hanger, its surface contour, under the tension of the spring, being such as to correspond to the contour of the shoulders and neck part of 10 the coat, substantially as herein set forth.

2. A coat or like hanger comprising two half-frame parts, a plate to which the half-frame parts are pivotally connected, the said plate being shorter than the full width 15 of the half-frame parts and the half frame parts at one side being bent inward to suit the shortened plate, a further plate directly over the first named plate, means for pivotally connecting the upper plate to the 20 half-frame parts and holding the upper plate at the required distance from the lower plate, a spring connected at its ends to the two plates respectively and by its tension holding the plates at their shortest distance apart, and a covering of cloth for the upper parts of the hanger secured by its edges to the half frame parts, to the upper plate and to the means on one side of the hanger for connecting the top plate to the half frame 30 parts substantially as herein set forth.

3. A coat or like hanger comprising two

half frame parts, a plate to which the half-frame parts are pivotally connected, a further and shorter plate directly over the first named plate, means pivotally connected 35 for holding the upper plate at the required distance from the lower plate and allowing the half frame parts to fold over against the other, the distance of the pivots at each end of the half frame parts from each other 40 being greater than the distance between the free ends of the half frame parts when folded, a spring connected at its ends to the two plates respectively and by its tension normally holding the plates at their shortest 45 distance apart and when the half frame parts are folded to lie alongside each other holding the said parts together at their free ends until forcibly separated, a covering of cloth for the upper parts of the hanger, the 50 cloth allowing of its being held taut and to the contour of the shoulders and neck of a coat under the tension of the spring, or allowing the hanger to be folded up substantially as herein set forth.

55
In witness whereof I have hereunto set my hand in the presence of two witnesses.

JOHN GEORGE BRENNER.
